UNITED STATES PATENT OFFICE.

WILLIAM P. CORNELL, OF CHARLESTON, SOUTH CAROLINA.

TAKE-UP DEVICE FOR TELEPHONE-CORDS.

1,179,700.

Specification of Letters Patent. Patented Apr. 18, 1916.

Application filed July 13, 1914. Serial No. 850,574.

To all whom it may concern:

Be it known that I, WILLIAM P. CORNELL, a citizen of the United States, and a resident of Charleston, South Carolina, have invented certain new and useful Improvements in Take-Up Devices for Telephone-Cords, of which the following is a specification accompanied by drawings.

This invention relates to a device for taking up the slack of the receiver cord of a telephone, although the invention may be applied to different analogous purposes.

The receiver cord usually runs from the receiver to the base of the telephone stand and then upwardly through the post to the base of the mouth-piece, and sufficient length of cord is provided to permit the receiver to be removed from the hook and placed at the ear of the party using the telephone. This receiver cord frequently becomes tangled and catches among papers or upon articles upon the desk or other support for the telephone stand.

My improvement consists of a device for automatically taking up the slack in the cord, but which permits the cord to be extended in use.

In accordance with this invention the cord always remains in a coil adjacent the telephone stand or post when not in use, the cord cannot become tangled and does not become mixed up with papers and articles on the desk.

The invention is illustrated in one of its preferred forms in the accompanying drawings, in which—

Figure 1 is a perspective view of the telephone stand provided with the improvements, showing the telephone cord in coiled position; Fig. 2 is a detail perspective view showing the telephone cord extended; Fig. 3 is a detail side view of a portion of one form of my flexible spring; Fig. 4 is a transverse view or end view of Fig. 3; Fig. 5 is a side view of a portion of a modified device; and Fig. 6 is a transverse end view of Fig. 5.

Referring to the drawings, A represents the base of an ordinary telephone stand having the post B and mouthpiece C.

D represents the telephone hook and E the receiver. The telephone cord F extends from the receiver at one end to the base A and my improved device for taking up slack comprises flexible means secured to the telephone cord F substantially throughout its

length and adapted to coil and uncoil as the telephone cord is relaxed, as shown in Fig. 1, or extended, as shown in Fig. 2. This device for automatically taking up the slack in the receiver cord, preferably comprises a coiled spring G suitably secured in any desired manner to the receiver cord substantially along its entire length. The coiled spring may be formed of flexible spiral spring wire of any desired metal, as for instance, brass wire and in the form shown in the drawings this spiral spring is provided with cross pieces or fingers H which may be soldered thereto at suitable intervals, as shown in Figs. 1, 2, 3 and 4, or else these fingers or hooks may be in the form shown in Figs. 5 and 6, comprising pieces of wire J, looped around the spring G instead of being soldered thereto. The telephone cord F is placed in the loops and the ends a of the loops are bent down around the cord, so that the cord conforms to the convolutions of the spring and as the spring is extended by taking up the telephone receiver E, the cord is also extended, but as the spring is relaxed, the telephone cord is automatically coiled into a substantially small compass, as illustrated in Fig. 1.

I am not to be understood as limiting the invention to the specific constructions of spring shown in the figures, because the spiral spring may be secured to the cord by other means than those shown.

This device has been found to operate efficiently and well in actual use and it is not only a great convenience, but saves wear and tear on the telephone cord, which is not so apt to become broken and the covering of the cord is protected against wear.

I claim and desire to obtain by Letters Patent the following:

1. The combination with a movable telephone desk-stand, telephone receiver and receiver support or hook, and flexible telephone cord connected to the receiver at one end, and entering the base of the stand at the other end, of a continuous flexible spiral spring to which the telephone cord conforms and to which said cord is secured substantially throughout its length, whereby the spring takes up the slack in the cord when the receiver is placed on the hook.

2. As a new and improved article of manufacture, a device adapted to be applied externally to the telephone cord of a tele-

phone for taking up the slack, said device comprising a flexible spiral of spring wire, the convolutions of which are provided with means for securing the device to the telephone cord, substantially throughout its length.

In testimony whereof I have signed this

specification in the presence of two subscribing witnesses.

WILLIAM P. CORNELL.
